[57] ABSTRACT

A dredge in which the barge thereof carries a pair of forwardly located spuds each positioned on opposite sides of the dredge and a rearwardly located spud which is carried by an extendible portion of the barge at its aft end. The pair of spuds at the fore end portion of the barge are shiftable longitudinally of the barge along its sides. With all three spuds embedded in the underlying water bottom, the barge through cylinder means is pushed ahead relative to the rear spud between the forward two pairs of spuds as the dredging operation progresses.

DREDGE HAVING IMPROVED PROPELLING MEANS

SUMMARY OF THE INVENTION

This invention relates to a dredge having improved propelling means.

The dredge of this invention includes a barge part having a hull which is adapted for flotation. A ladder is pivotally connected to the extendible at its forward end. A pair of spuds is mounted at the fore end portion of the hull with each spud being located at one side of the hull and being associated with means permitting the spuds to shift longitudinally relative to the barge part along the hull sides. At least one other spud is located at the aft end of the barge part and is supported by an extendible section of the barge part. The pair of forwardly located spuds and the rearwardly located spud are lowered into the water and embedded in the underlying water bottom. Means are provided for shifting the hull forwardly relative to the anchored rear spud and between the pair of anchored spuds located at the fore end portion of the hull. In this manner the hull and ladder are urged selectively forwardly during the dredging operation.

It is an object of this invention to provide a dredge having improved means of propulsion during the dredging operation.

Another object of this invention is to provide a dredge having a pair of forwardly located laterally spaced spuds between which the hull of the dredge is urged by at least one rearwardly positioned spud during the dredging operation.

Other objects of this invention will become apparent upon a reading of the invention's description.

BRIEF DESCRIPTION OF THE DRAWINGS

FIG. 1 is a top plan view of one embodiment of a dredge which includes the propelling means of my invention.

FIG. 2 is a side elevational view of the dredge of FIG. 1.

FIG. 3 is a fragmentary sectional view taken along line 3-3 of FIG. 2.

FIG. 4 is a fragmentary elevational view showing the spuds of the dredge embedded in the underlying water bottom with the dredge located in a first operative position.

FIG. 5 is a fragmentary elevational view showing the spuds embedded in the underlying water bottom with the dredge having been urged into another operative position.

DESCRIPTION OF THE PREFERRED EMBODIMENT

The preferred embodiment illustrated is not intended to be exhaustive or to limit the invention to the precise form disclosed. It is chosen and described in order to best explain the principles of the invention and its application and practical use to thereby enable others skilled in the art to best utilize the invention.

Dredge 10 shown in the drawings includes a barge part 12 which includes a hull 13 supporting a cabin 15. A ladder part 14 is pivotally connected to hull 13. Ladder 14 is of a float-type construction which pivotally supports a cutter 16. Cutter 16 is drive connected to a hull supported motor 18 by a drive shaft 20. An over-

head pulley support system 22 connected between barge part 12 and cutter 16 serves to raise and lower and to laterally shift the cutter relative to the barge part. The dredge thus far described is of a standard 5 commercial application.

The means for propelling dredge 10 during a dredging operation includes a pair of forwardly mounted spuds 24 and a rearwardly mounted spud 26. Spuds 24 and 26 are each housed in a suitable sleeve 28 and are 10 connected by a cable 30 which extends from the upper end to the lower end of the spud. Each cable 30 is wound around a pulley 32 which in turn is drive connected to a motor 34 secured to each sleeve 28. Rotation of a pulley 32 will cause the cable 30 wound there-around to be pulled upwardly or downwardly with the connected spud being raised or lowered, depending upon the direction of rotation of the associated motor 34. The means for individually raising and lowering spuds 24 and 26 may vary from construction to construction of the dredge.

Forward spuds 24 are located at opposite sides of hull 13 and are each supported for longitudinal shiftable movement relative to the hull by means of upper and lower spaced pairs of rollers 36. The rollers 36 supporting each spud 24 are rotatably secured to the spud's sleeve 28 and fit within spaced parallel guides 38 which allow the spud to be shifted fore and aft along the guides relative to the hull as illustrated in FIGS. 4 and 5. Spud 26 at the aft end of barge part 12 has its sleeve 28 secured to a support 40. Support 40 is connected to hull 13 of the barge part by means of a pair of hydraulic power cylinder members 42. Each cylinder member 42 includes a cylinder part 44 and an extendible retractable rod part 46. Cylinder parts 44 are carried by hull 13 while the free ends of rod parts 46 are secured to opposite transverse portions of support 40. The simultaneous actuation of cylinder members 42 causes the hull to be shifted relative to support 40.

In operation, dredge 10 will be floating upon a body 40 of water 48 having a bottom 50. Spuds 24 which are raised will be pushed toward the fore end of the barge part into the forward position shown in FIGS. 1 and 2. The spuds 24 and 26 are then lowered into water 48 and embedded in water bottom 50 by actuation of motors 34. The dredging operation starts with cutter 16 lowered and located in cutting position along bottom 50 or the bank of water 48 and with cylinder members 42 being actuated, causing hull 13 to be pushed away from support 40 and urged forwardly between spuds 24. Hull 13 is so urged forwardly at a selected rate of speed until the spuds 24 are located at the rear ends of the guides 38 as illustrated in FIG. 5. At this time cylinder members 42 are deactivated and rear spud 26 45 raised through the actuation of its motor 34. Once the lower end of spud 26 is free from water bottom 50, cylinder members 42 will again be actuated to cause support 40 to be drawn forwardly toward hull 13. When support 40 is positioned in its forwardmost position adjacent the hull 13, the cylinder members 42 are deactivated again and aft spud 26 again lowered and embedded into water bottom 50. Once spud 26 has been re-embedded into the water bottom, the spuds 24 will be raised and freed from bottom 50 and slid forwardly along guides 38. After both spuds 24 have been shifted into their forwardmost position along guides 38, the spuds will be lowered into and re-embedded in water bottom 50, at which time cylinder members 42 are 55 60 65 66

again actuated to cause hull 13 to be urged forwardly relative to support 40 and between spuds 24. This above described sequential operation of moving spuds 24 and 26 and actuating cylinder members 42 is repeated until a particular run of a dredging operation has been completed. It is to be understood that in some constructions of this invention it may be preferable to have two spuds 26 carried by support 40.

It is to be understood that the invention is not to be limited to the details above given, but may be modified within the scope of the appended claims.

What I claim is:

1. In a dredge having a barge part which includes a hull adapted for flotation and having fore and aft ends and port and starboard sides extending between said ends, a ladder pivotally connected to said hull at its fore end, the improvement comprising a first spud located rearwardly of said hull aft end, means for raising and lowering said first spud into and out of embedded contact with the bottom of a water body upon which said hull then floats, a pair of vertically oriented second spuds, one of said second spuds located on the port side of said hull forwardly of said first spud, the other of said

second spuds located on the starboard side of said hull forwardly of said first spud, means for raising and lowering said second spuds in their vertical orientation into and out of embedded contact with the bottom of said water body with said hull floating thereon, means securing said one second spud to the port side of said hull for guided shiftable movement of said one second spud along said port side independently of said raising and lowering of said one second spud, means securing said other second spud to the starboard side of said hull for guided shiftable movement of said other second spud along said starboard side independently of said raising and lowering of said other second spud, means connecting said first spud to said hull for shifting said hull forwardly relative to said spud and between said second spuds when in embedded contact with said bottom and for shifting said first spud rearwardly relative to said hull when said first spud is raised out of embedded contact with said bottom.

2. The dredge of claim 1 wherein said second spuds are directly oppositely located across said hull.
